ROTARY OPERATED SNAP ACTING DEVICE

Wilbert A. Martin, Freeport, Ill., assignor to First
Industrial Corporation, Wilmington, Del., a
corporation of Delaware

Application February 18, 1946, Serial No. 648,343

6 Claims. (Cl. 74—97)

1

This invention relates to snap action devices and particularly to a precision type snap acting electric switch having a built-in rotative operating member.

By a "precision type" switch, I refer here to the type illustrated by the Eaton Patent 2,170,748 and various modifications of it.

Among the objects of this invention is the provision of a precision type switch which is highly compact by reason of the facts that: (1) it has a built-in operating member which is limitedly rotative, thereby dispensing with the volume of an extra "actuator"; (2) its operating member has a substantial amount of overtravel in both rotative directions beyond the contact-changing position; and (3) it is operable by very light forces. Thus, it is particularly adapted for use in coin operated devices such as juke boxes, pay telephones, and the like, where the switch must: (1) be compact; (2) operate with a certain amount of overtravel; and (3) be operable by a featherlike force which may be as low as the weight of a dime (2 grams). The present invention resides in certain novel features of construction, combination of parts, and arrangement of apparatus, particularly set forth in the claims, and is illustrated by the specific embodiment herein shown and described by way of example.

In the drawings:

Figure 1 is a side view with the cover removed of one embodiment of my invention;

Figs. 1a and 1b are top and end views, respectively, of Figure 1;

Fig. 2 is a view similar to Figure 1 showing the movable parts in the opposite or current-carrying position;

Fig. 3 is a sectional view of Fig. 2 taken on the line 3—3, and

Fig. 4 is an exploded perspective view of the separable parts of the switch.

Referring now more particularly to the figures, the switch illustrated has a base plate 21 onto which the cover plate 22 is adapted to be mounted by means of the rivet 23. Terminal members 24 and 26, having apertures 27 for attachment to external wires (not shown), are mounted on the base plate 21 by single rivets 28 and 29, respectively. An operating member 31, having the hook-like cam member 32 riveted to its inner end, is rotatably journaled within the circular opening 33 formed in the base plate. The operating member 31 is restrained against reciprocal movement by means of its shoulder portion 34 and the C-washer or snap ring 36. The outer end portion of the operating member may

2

be formed in any suitable manner to receive a stiff wire or other rotatable member, in this case being provided with the drilled hole 37 and the extensions 38.

5 A snap acting spring member generally designated 39 comprises a tension member which is made up of a pair of elongated tension elements 41 joined by end portions 42 and 43. The latter end portion carries the movable contact 44 and 10 also has attached thereto a spring strip or compression element 46 which, in the assembled switch, is normally bowed in longitudinal compression. The terminal member 24 has formed integral with it an upstanding or anchor portion 47, so-called because the spring strip end 48 and the knife edge 49 of the elongated actuating member 51 are "anchored" or pivoted on it in grooves 52 and 53 respectively. The anchor portion 47 serves additionally as an adjustable (by 15 bending) means of limiting counterclockwise rotation of the actuator 51 around its lower or pivoted end portion. The actuating member 51 has the tension member end portion 42 pivotally engaged within its groove 54; and at its upper 20 portion it has the operating surface 56 slidably engaged with the operating surface or edge 57 of the cam 32.

The particular embodiment shown illustrates a self-returning type of switch in which the 25 parts are arranged so they will tend to assume the positions shown in Figure 1 where the movable contact 44 abuts the stop 61 formed as an integral extension of the terminal member 24. This is referred to as the normal position of the 30 switch at which the circuit between the terminals 24 and 26 is broken. Rotation of the cam 32 by the operating member 31 will cause it to move the actuating member 51 arcuately about the pivot edge 49, at the same time lifting the end 42 of the tension member. It will be noted that in Figure 1 the tension member is located just below the pivot groove 52. When the tension member is moved upward by the cam, it will pass through a position or axis of maximum stress where the 35 pivot groove 52 is aligned with the tension member, and from this position it will snap upwardly into engagement with the stationary contact 63 which is formed as an integral part of the terminal member 26. The parts will then be in the 40 positions shown in Fig. 2, terminals 24 and 26 being connected through the spring member 39. In order that the parts be self-returning to the 45 Figure 1 position they must be so arranged that the tension member will never cross over the 50 groove 53; it will be noted that, to this end, the 55

groove 53 is formed somewhat above the groove 52 on the anchor 47. The anchor portion 47 may be suitably bent during assembly of the switch so as to limit the counterclockwise rotation of the actuating member 51 to prevent the tension member from being moved above it.

When the rotative force is released from the operating member 31 the actuating member 51 will be rotated by energy stored in the spring 39 until the tension member has once more passed through the axis of maximum stress, at which time the contact 44 will be snapped downwardly out of engagement with the stationary contact 62 and the parts will once more assume the normal positions shown in Figure 1.

Reference will now be made to the overtravel which may be built into the switch. Counterclockwise rotation of the cam 32 is limited by abutment with the stop 58 formed in the base portion; and clockwise rotation is limited by a similar stop 59. It will be noted that in Figure 1 the normal position of the cam 32 is such that it can be moved clockwise before abutting the stop 59; this represents overtravel or freedom of movement beyond the normal position in the clockwise direction. Similarly, in the counterclockwise direction, the amount of travel beyond the normal position may be determined by the position of the stop 58, which may be set a number of degrees beyond the operating position as desired. With this construction, it is practical to have from 20 to 25° of travel in each direction beyond the normal or Figure 1 position.

The cam 32 is made to operate the actuator 51 in either rotative direction; however, lower operating forces are required when it is moved counterclockwise by reason of the fact that the force is applied farther from the pivot 49. To this end, the stops 58 may be positioned so as to prevent clockwise but permit counterclockwise operative movement from the normal position.

In Figures 1, 2 and 4 the position of the center line or axis of the cam 32 is indicated by a small "x" designated 62. It will be noted that in both the operative positions, Figures 1 and 2, the actuating member 51 is intersected by this center line. In other words, the actuating member and cam operating surfaces 56 and 57 are so positioned with respect to the axis of rotation 62 that rotation of the cam 32 causes the cam engaging surface 56 to move toward, and not away from, the axis 62. I have found this preferable since with this arrangement the force tending to return the cam to the normal position increases rather than decreases as the cam is turned.

Although only one embodiment of the device is described and illustrated it will be understood that the invention is not limited thereto but is limited only in accordance with the scope of the appended claims.

I claim:

1. A snap acting device, comprising spaced tension members interconnected at opposite ends, one of said ends being free to move between preselected positions with a snap action, a compression member disposed between said tension members and having an end interconnected with the free end and the opposite end in spaced relation with the other end of the spaced tension members, a bracket disposed between said spaced tension members and pivotally supporting the opposite end of the compression member, a lever disposed between said spaced tension members and supporting said other end of the tension members; said lever having a projection thereon

engaging said bracket on the side thereof opposite the pivotal support for the compression member to form a fulcrum, said tension and compression members in the supported position forming a snap spring system having an axis of maximum stress, and cam means engaging said lever at a position spaced from said fulcrum to move said lever a predetermined distance whereby said other end of the tension members moves relative to the pivotally supported end of the compression member through the axis of maximum stress.

2. A snap acting device, comprising spaced first stressed members interconnected at opposite ends, one of said ends being free to move between preselected positions with a snap action, a second stressed member disposed between said first stressed members and having an end interconnected with said free end and the opposite end in spaced relation with the other end of the spaced first stressed members, a bracket disposed between said spaced first stressed members and pivotally supporting the opposite end of the second stressed member, a lever disposed between said spaced first stressed members and supporting said opposite end of the first stressed members; said lever having a projection thereon engaging said bracket on the side thereof opposite the pivotal support for the second stressed member to form a fulcrum, said first and second stressed members in the supported position forming a snap spring system having an axis of maximum stress, and cam means engaging said lever at a position spaced from said fulcrum to move said lever a predetermined distance whereby said opposite end of the first stressed members moves relative to the pivotally supported end of the second stressed member to move said snap spring through its axis of maximum stress.

3. In a snap action switch, the combination of a base, opposed stops mounted on said base, a bracket mounted on said base and having grooves formed on opposite sides thereof in spaced relation, a snap spring system comprising a compression member and a tension member, one end of each of said tension and compression members being interconnected and free to move between the opposed stops with a snap action, the opposite end of said compression member being pivotally supported in one of said grooves, and the opposite end of said tension member being in spaced relation with the opposite end of said compression member, a lever supporting the opposite end of said tension member and having a projection pivotally received in said other groove, said lever being shaped so that movement thereof about its pivotal support moves said tension member relative to the pivotal support of said compression member, and means rotatable about an axis engaging said lever to effect movement thereof.

4. In a snap action switch, the combination of a base, a bracket mounted on said base, a snap spring system comprising a compression member and a tension member, one end of each of said tension and compression members being interconnected and free to move between preselected positions with a snap action, the opposite end of said compression member being pivotally supported on one side of said bracket, and the opposite end of said tension member being in spaced relation with the opposite end of said compression member, a lever pivotally mounted on the opposite side of said bracket and shaped to support the opposite end of said tension member, said lever being shaped so that movement there-

of about its pivotal support moves said opposite end of the tension member relative to the pivotal support of said compression member, and cam means rotatable about an axis and engaging said lever to effect the aforesaid movement.

5. In a snap action switch, the combination of a snap spring system comprising a compression member and a tension member, one end of each of said tension and compression members being interconnected and free to move between pre-selected positions, means for pivotally supporting the opposite end of said compression member, the opposite end of said tension member being in spaced relation with the opposite end of said compression member, a rigid lever for supporting the opposite end of said tension member, means for fulcruming said lever so that movement of said lever moves said opposite end of the tension member relative to the pivotal support of said compression member, and cam means rotatable about an axis and engaging said lever at a position spaced from said fulcruming means to effect the aforesaid movement whereby said free end moves between the preselected positions with a snap action.

6. In a snap spring system, the combination of, a tension member having an end free to move between spaced positions with a snap action and an opposite end portion, a compression member having an end interconnected with said free end and having an opposite end portion in spaced relation with said opposite end portion of the tension member, means forming a fixed mounting for one of said opposite end portions, a lever providing a mounting for the other of said opposite end portions, means forming a pivot for said lever, and a cam engaging said lever to move the opposite end portion supported by said lever through an axis of maximum stress to move said free end between the spaced positions.
